Primary Examiner — Sandra Snapp*Assistant Examiner* — Altaira J Swangin(74) *Attorney, Agent, or Firm* — Bayramoglu Law Offices LLC(57) **CLAIM**

The ornamental design for an airtight canister, as shown and described.

DESCRIPTION

FIG. 1 is a front, top and right perspective view of an airtight canister showing my new design;

FIG. 2 is a front view thereof;

FIG. 3 is a rear view thereof;

FIG. 4 is a right side view thereof;

FIG. 5 is a top view thereof;

FIG. 6 is a bottom view thereof; and,

FIG. 7 is a front, bottom and right perspective view thereof. A left side view is omitted since the left side is identical to the right side view.

1 Claim, 7 Drawing Sheets(56)
